BALLOON

Thomas A. Tredway, P.O. Box 336, Denison, Tex.

Filed Nov. 14, 1962, Ser. No. 72,498

Term of patent 14 years

(Cl. D34—15)

Fig. 3

Fig. 1

Fig. 2

Fig. 4

FIGURE 1 is a front elevational view of a balloon embodying my new design, in a deflated condition;

FIGURE 2 is an elevational view taken from one side thereof, the other side view being substantially identical;

FIGURE 3 is a top plan view thereof; and

FIGURE 4 is a bottom plan view thereof.

I claim:

The ornamental design for a balloon, as shown.
